Isaac Joseph Aronowitz, Cambridge, England

Application June 28, 1948, Serial No. 147,247
In Great Britain July 22, 1947

Term of patent 14 years

(Cl. D85—8)

To all whom it may concern:

Be it known that I, Isaac Joseph Aronowitz, a British subject, of 302 Hills Road, Cambridge, England, whose post office address is the same, have invented a new, original, and ornamental Design for a Tobacco Pipe Cover, of which the following is a specification, reference being had to the accompanying drawings, forming part thereof.

I claim:

The ornamental design for a tobacco pipe cover, as shown and described.

ISAAC JOSEPH ARONOWITZ.
